UNITED STATES PATENT OFFICE.

NORMAN G. GLATTFELTER, OF DRUMMONDSVILLE, QUEBEC, CANADA, AND KARL BABERADT, OF HAZLETON, PENNSYLVANIA, ASSIGNORS TO LOUIS ROESSEL & CO., INC., OF NEW YORK, N. Y., A CORPORATION OF PENNSYLVANIA.

SPINNING SPINDLE.

Application filed June 2, 1925. Serial No. 34,305.

This invention relates to spinning spindles such as are generally used in silk and cotton mills, and, broadly considered, has for its principal object and purpose to provide simple and easily operated means for throwing the spindle out of engagement with the driving wheel and quickly bringing the spindle to a complete stop so that the operator may have the free use of both hands in connecting up the end of the thread.

It is another and more particular object of our invention to provide a pivotally-mounted lever having means to coat with the pivoted spindle carrying arm whereby 15 when the lever is moved in one direction the spindle is thrown out of engagement with the face of the driving wheel, and an adjustable brake means carried by said lever and adapted to automatically engage the rotating spindle as the latter is moved away 20 from the driving wheel whereby said spindle is quickly brought to a complete stop.

It is also a further object of our present improvements to provide a novel mounting 25 of the spindle releasing lever and a simple and effective latch means therefor to retain said lever in its release position.

With the above and other objects in view, the invention consists in the improved releasing device for spinning spindles, and in the form, proportion, and relative arrangement of the several parts thereof as will be hereinafter more fully described, illustrated in the accompanying drawings, and subsequently incorporated in the subjoined 35 claims.

In the drawings, wherein we have shown one simple and satisfactory embodiment of the invention, and in which similar reference characters designate corresponding parts throughout the several views,—

Figure 1 is a side elevation illustrating one embodiment of our present improvements;

Fig. 2 is a front view thereof;

Fig. 3 is a plan view, the spindle being shown in section and in engagement with the driving wheel, and

Fig. 4 is a similar view but showing the 50 relative position of the parts after the spindle has been disengaged from the driving wheel.

For the purpose of illustrating one application of our invention, in the accompany-

ing drawings we have shown a pair of vertically spaced, horizontally positioned rails 5 which extend along the front of the machine and upon which the spaced spindle supports are mounted. In the present instance, we have shown these rails as of 60 cylindrical form and each of the spindle supports includes a pair of plates 6 and 7, respectively, which are provided in their opposed faces with concave seats to receive the rails 5. Between said rails these plates 65 are connected with each other by means of the bolt 8 whereby they are rigidly clamped upon the rails.

The plate 6 at its upper end is formed with a laterally projecting arm 9 upon which the 70 angular spindle carrying bracket 10 is pivotally mounted at one of its ends, as at 11. The spindle 12, which is rotatably supported in the other end of this bracket may be of any conventional type and is provided with 75 a cylindrically enlarged section 13 for contact with the facing 15 on the driving wheel 14, said facing preferably consisting of leather or other suitable material of light frictional character.

The plate 7 is provided at its upper end with a horizontally projecting lug 16 upon which the lever 17 is supported intermediate of its ends for free pivotal movement about a bolt 18 threaded or otherwise fixed in said 85 lug. Between the head of said bolt and the lever 17 a coil spring 19 is interposed. One end of the lever 17 is provided with a downwardly projecting finger 20 positioned against one side of the spindle carrying arm 90 10 at the upper end thereof and adjacent to its pivot 11.

At the opposite side of the pivot bolt 18 with respect to the finger 20, the lever 17 has a tooth 21 formed on the under side 95 thereof adapted for movement over a series of rack teeth 23 formed upon the end of a lateral extension 22 on the upper end of the plate 7. By this means the lever 17 is held against a casual pivotal movement on the bolt 18, the spring 19 acting upon said lever to maintain its tooth 21 in engagement with the teeth of the rack 23 but readily yielding so that said tooth 21 may move over the rack upon the application of lateral pressure 105 against the end of the lever.

The end of the lever 17 which is provided with the finger 20 also has a pin or stud

24 projecting upwardly therefrom. This pin is loosely engaged in an opening formed in an arm 25 engaged upon the upper side of the lever 17. This arm at one end is 5 formed with an obliquely inclined curved section 26 extending over the driving wheel 14 and located at one side of the spindle 12. The end of this curved section 26 of the arm 25 is provided with a suitably formed 10 holder for a brake shoe 27 of a suitable frictional material.

The inner end of the arm 25 is provided with a slot 28 extending at right angles to the axis of said arm, said slot receiving a 15 screw 29 which is threaded in the lever 17. By means of this screw 29, the arm 25 may be securely clamped in an adjusted position upon the end of the lever whereby the brake shoe 27 may be caused to properly bear upon 20 the spindle with the described frictional pressure.

Having above described the several mechanical features of the device, its operation will be understood as follows. Assuming 25 that the spindle is being driven by frictional contact of the facing leather 15 on the driving wheel 14 with the part 13 of said spindle, and that it is desired to release the spindle from such driving engagement with 30 the wheel, this may be easily done by simply moving the outer end of the lever 17 to the left from the position shown in Fig. 3 of the drawings. The finger 20 on said lever is thus caused to bear against the pivoted arm 35 10 and swing said arm to the right, thereby carrying the part 13 of the spindle away from the driving face of the wheel 14. In this movement of the lever 17 the brake shoe 27 is automatically brought into frictional 40 bearing engagement against the part 13 of the spindle in the manner illustrated in Fig. 4 of the drawings, as it will be observed that the arc of movement of the spindle is much shorter than that of the brake shoe. Thus 45 when the spindle reaches its disengaged position, it is simultaneously engaged by the brake shoe 27 so that the frictional resistance offered by said shoe quickly brings the rotating spindle to a complete stop. 50 Thus, the operator may employ both of his hands in connecting up the loose end of the thread and it is not necessary for him to first stop the rotation of the spindle. After the connection has been made, the lever is 55 again moved to its former position as shown in Fig. 3 and the spindle returned to its operative position in engagement with the driving face of the wheel 14. If desired, it will be understood that a suitable spring 60 may be provided acting upon the arm 10 to normally hold the spindle in the latter position. However, in the present instance, the operator after connecting the thread, moves the spindle arm 10 by hand, and said arm 65 being against the finger 20 on the lever

shifts the lever over the rack 23 against the action of the spring 19.

From the foregoing description considered in connection with the accompanying drawing, the several features of our present 70 improvements and the advantages thereof in practical use will be readily understood. Thus, we have found that by means of such a device, a gain of approximately 75% in the speed with which such spinning 75 machines may be operated can be attained. By means of our improvements, a single spindle, or as many spindles as desired can be quickly thrown out of operation at any 80 time, thereby reducing wear upon the leather friction surface of the drive wheel or wheels and correspondingly reducing the expense incident to the replacement of such friction surfaces and prolonging the life thereof.

85 We have herein disclosed what we regard as a practical and satisfactory embodiment of our present improvements. Nevertheless, it will be apparent to those familiar with this art that the device might also be incorporated in various other alternative constructions, and we therefore, reserve the privilege of adopting all such legitimate changes in the form, proportion and relative arrangement of its several parts 95 as may be fairly embodied within the spirit and scope of the invention as claimed.

We claim:

1. In combination with a pivotally mounted spindle carrying arm and a drive 100 wheel to engage one side of the spindle, a pivotally mounted lever having means at one of its ends coacting with the spindle arm when said lever is moved in one direction to move said arm and disengage the 105 spindle from the driving wheel, and means for yieldingly latching said lever against movement in the reverse direction.

2. In combination with a pivotally mounted spindle carrying arm and a drive 110 wheel to engage one side of the spindle, a pivotally mounted lever having means at one of its ends coacting with the spindle arm when said lever is moved in one direction to move said arm and disengage the 115 spindle from the driving wheel, and braking means carried by said lever and automatically engaging the spindle as the latter moves out of contact with the driving wheel whereby rotation of the spindle is stopped. 120

3. In combination with a pivotally mounted spindle carrying arm and a drive wheel to engage one side of the spindle, a pivotally mounted lever having means at one of its ends coacting with the spindle 125 arm when said lever is moved in one direction to move said arm and disengage the spindle from the driving wheel, an arm mounted upon one end of said lever and having a curved section extending around 130

one side of the spindle, and a brake shoe on the end of said curved section of the arm adapted to automatically engage the spindle as the latter is moved out of contact with the driving wheel whereby the rotation of said spindle is brought to a stop.

4. In combination with a pivotally mounted spindle carrying arm and a drive wheel to engage one side of the spindle, a pivotally mounted lever having means at one of its ends coacting with the spindle arm when said lever is moved in one direction to move said arm and disengage the spindle from the driving wheel, an arm mounted upon one end of said lever and having a curved section extending around one side of the spindle, a brake shoe on the end of said curved section of the arm adapted to automatically engage the spindle as the latter is moved out of contact with the driving wheel whereby the rotation of said spindle is brought to a stop, and means for adjusting said arm relative to the lever to compensate for wear upon the brake shoe.
5. In combination with a pivotally mounted spindle carrying arm and a drive wheel to engage one side of the spindle, a pivotally mounted lever having means at one of its ends coacting with the spindle arm when said lever is moved in one direction to move said arm and disengage the spindle from the driving wheel, an arm pivotally mounted upon one end of said lever for adjustment relative thereto, a brake shoe on one end of said arm adapted to automatically coact with the spindle when the latter is moved out of engagement with the driving wheel to stop the rotation of said spindle, and means for securing said arm in its adjusted position relative to the lever.
6. In combination with a pivotally

mounted spindle carrying arm and a drive wheel to engage one side of the spindle, a pivotally mounted lever having means at one of its ends coacting with the spindle arm when said lever is moved in one direction to move said arm and disengage the spindle from the driving wheel, an arm pivotally mounted upon one end of said lever for adjustment relative thereto, a brake shoe on one end of said arm adapted to automatically coact with the spindle when the latter is moved out of engagement with the driving wheel to stop the rotation of said spindle, means for securing said arm in its adjusted position relative to the lever, and means for yieldingly latching said lever against pivotal movement.

7. In combination with a driving wheel and a spindle mounted for bodily movement to and from its operative position with respect to said driving wheel, manually operable means for moving said spindle to its inoperative position, and means for applying braking pressure to the spindle when moved to such inoperative position to stop the rotation of the same.

8. In combination with a driving wheel and a spindle mounted for bodily swinging movement in an arcuate path to and from its operative position with respect to said driving wheel, a pivoted manually operable lever having means to engage the spindle and move the same to its inoperative position, and a brake shoe adapted to engage one side of the spindle to check the acquired rotative momentum thereof when the spindle is moved to such inoperative position.

In testimony that we claim the foregoing as our invention, we have signed our names thereto.

NORMAN G. GLATTFELTER.
